United States Patent Office.

GEORGE F. MEACHAM, OF NEWTON, ASSIGNOR TO JAMES W. TUFTS, OF MEDFORD, MASSACHUSETTS.

Design No. 4,620, dated January 31, 1871.

DESIGN FOR A SODA-FOUNTAIN.

The Schedule referred to in these Letters Patent and making part of the same.

To all whom it may concern:

Be it known that I, GEORGE F. MEACHAM, of Newton, in the county of Middlesex and State of Massachusetts, have invented and produced a new and original Design for the Casing of a Soda-Water Apparatus, of which the following is a full, clear, and exact description, reference being had to the accompanying photograph making part of this specification.

The object of this design is to relieve the rectangular casing of a soda-water apparatus of its box-like appearance, and consists in chamfering or beveling off the upper corners so as to contract the size of the apparatus at its top.

In the photograph—

A represents the casing of a soda-water apparatus, the lower portion of which is of rectangular form.

Each of the upper corners is chamfered or beveled off at α , so as to diminish the size of the top of the apparatus, and thus relieve it of the box-like appearance which it would otherwise present, the design thus produced being unique and ornamental.

What I claim as my invention, and desire to secure by Letters Patent, is—

The design for the casing of a soda-water apparatus herein shown and described.

Witness my hand this 1st day of December, A. D. 1870.

GEO. F. MEACHAM.
